UNITED STATES PATENT OFFICE.

GASTON DOLNE-DEHAN, OF JUAN LES PINS, FRANCE.

TWO-STROKE COMBUSTION ENGINE.

Application filed July 11, 1924, Serial No. 725,510, and in Belgium July 16, 1923.

This invention relates to two-stroke engines in which the fuel supply is effected by a plurality of spraying nozzles simultaneously projecting the fuel on a metallic and electrically heated band while the superheated air from the scavenging charge energetically stirs the jets of liquid in the proximity of the ignition device.

This arrangement permits in high pressure engines, the air to be first compressed alone and the fuel to be thereafter injected at the moment of combustion which obviously must be as brief and complete as possible.

15 In the accompanying drawing wherein an approved embodiment of the invention is illustrated,

Fig. 1 is a fragmentary vertical section of an engine constructed in accordance with the invention showing the piston in elevated position.

Fig. 2 is a similar view showing the piston lowered.

Fig. 3 is a diagrammatic view illustrating the disposition of the various fuel nozzles and air channels with respect to the igniting device.

The piston 1 carrying a sleeve like extension is arranged within the cylinder 2 and is adapted as it approaches the limit of its down stroke to uncover the exhaust port 3 which latter occupies substantially the entire circumference of the cylinder.

Immediately subsequent to the uncovering of the port 3, a series of inclined ports 4 uncover the upwardly converging passages 5 formed in the cylinder wall and the latter ports coacting with the port 3 effectively scavenge the cylinder throughout its entire length. The upper end of the cylinder is closed by a head 7 having the usual chamber therein for the passage of a cooling medium. Between the head 7 and the cylinder 2 is an annular chamber 8 receiving the sleeve extension of the piston during the upstroke of the latter.

The fluid sealing of the space 8 is secured by means of a series of packing rings 9 disposed above and below the passages 4. A wider packing ring 10 surrounding the upper part of the piston sleeve which collects a small quantity of oil on the cylinder wall and brings it over the edge of the sleeve toward the surface of the cylinder head.

The dimension of the annular chamber 8 is calculated so the compression increased

more rapidly in this chamber than in the combustion chamber, for an equal displacement of the piston.

The pressure in the space below the piston is relieved by ports 11 which are uncovered by the lower edge of the piston during the upward stroke thereof. An annular channel 12 in communication with the atmosphere supplies these ports which latter terminate in the cylinder at the same level as the scavenging passages 5 and are arranged intermediate the latter.

The injection of the liquid fuel is effected by means of the spraying nozzles 13 arranged about the cylinder and adapted to be uncovered when the piston approaches the limit of its up-stroke.

The spraying nozzles are inclined correspondingly to the passages 4 and are arranged to direct jets of fuel tangentially towards a circular groove 14 formed on the inner side of the cylinder head. The wall of which groove is faced with a metallic refractory band of platinum, nickel or other durable and non-fusible alloy rolled over nearly the entire circumference of an insulating cylinder 15 containing the electrodes for heating current of the metallic band or ignition wire.

The groove 14, in addition to insulating the band from the combustion chamber, communicates by means of channels 16 with an annular space 17 concentrically disposed within the cylinder and limited by cylinder head and the piston sleeve when the piston is moving upwardly.

As the passages 4 uncover the nozzles, a shoulder 18 of the sleeve enters the space 17 in which it slides with little friction, confines therein a small portion of the scavenging air already heated by the compression and by contact with the walls, and causes the air to pass through the channels 16 which are directed in the same tangential direction as the fuel jets towards the ignition groove 14 as clearly disclosed in Fig. 3.

It is clearly evident that the simultaneous action of the nozzles spraying the liquid fuel in the form of very fine jets and of the channels blowing out hot air, produces in the groove 14 an eddy carrying away the vapors produced by the highly heated band mixing it with the air of the combustion chamber and preventing the combustion being localized at the point of ignition. At the same time, the admission of air through the chan-

nels 16 tends to prevent the rapid accumulation of carbon on the heating surface of the band.

Among the advantages obtained by this arrangement as compared with those already known, it will be observed that the nozzles being covered during the whole period of compression and combustion, except the moment of their operation cannot 10 possibly permit the liquid fuel to escape into the combustion chamber, a defect well known in present types of engines which frequently results in damage and accident. Furthermore, the nozzles are protected from 15 deterioration caused by the high temperature of the cylinder.

Manometric needles 19 permit the individual regulation and cleaning of each nozzle. When the engine is inoperative the 20 cylinder head may be removed and the action of the nozzles inspected. Regulation is possible during operation and the multiplicity of nozzles renders the operation of the nozzle more reliable as in case of damage or 25 the like to one or more of the nozzles, the others may be so adjusted as to make up for the deficiency in fuel supply.

The current necessary for the operation of the heating band is comparatively slight 30 and use may be made of a small reducer transformer fed by a magneto or an alternator actuated by the engine during operation of the latter or by hand during its inoperativeness.

What I claim as new, and desire to secure 35 by Letters Patent is:—

1. In a two-stroke engine, a cylinder, a piston mounted in the cylinder having a sleeve like extension, a crank case, said piston having inclined ports therein at the base 40 of the sleeve extension, means for conducting compressed air from the engine crank case to the combustion chamber, a plurality of spraying nozzles arranged in the wall of 45 the cylinder, and means for regulating and cleaning each nozzle relative to the other nozzle.

2. In a two-stroke engine, a cylinder, a piston mounted in the cylinder having a sleeve like extension, a crank case, said piston 50 having inclined ports therein at the base of the sleeve extension, means for conducting compressed air from the engine crank case to the combustion chamber, a plurality of spraying nozzles arranged in the wall of 55 the cylinder.

3. An engine as claimed in claim 2 characterized by the provision of a cylinder head providing an annular chamber for receiving the extension sleeve, said cylinder head having an annular groove, an electrically heated metallic band in said groove, said nozzles being arranged to project liquid fuel tangentially of the groove whereby the fuel comes in contact with the metallic band. 60 65

4. An engine as claimed in claim 2 characterized by the provision of a cylinder head providing an annular chamber for receiving the extension sleeve, said cylinder head having an annular groove, an electrically heated 70 metallic band in said groove, said nozzles being arranged to project liquid fuel tangentially of the groove whereby the fuel comes in contact with the metallic band, a fuel supply pipe common to all of the nozzles, 75 and means for regulating and cleaning each nozzle individually.

5. An engine as claimed in claim 2 characterized by the provision of a cylinder head providing an annular chamber for receiving 80 the extension sleeve, said cylinder head having an annular groove, an electrically heated metallic band in said groove, said nozzles being arranged to project liquid fuel tangentially of the groove whereby the fuel 85 comes in contact with the metallic band, said cylinder head having a second groove therein and channels connecting the groove, and a shoulder on the piston adapted to enter the second groove and force air through the 90 channels into the first groove.

In testimony whereof I have signed my name to this specification.

DR. GASTON DOLNE-DEHAN.
